UNITED STATES PATENT OFFICE.

NEHEMIAH P. CORNEY, OF MONTVILLE, NEW JERSEY.

DESIGN FOR A STICKPIN.

Application filed November 30, 1925. Serial No. 15,585. Term of patent 3½ years.

To all whom it may concern:

Be it known that I, NEHEMIAH P. CORNEY, a citizen of the United States, residing at Montville, in the county of Morris and State of New Jersey, have invented a new, original, and ornamental Design for Stickpins, of which the following is a specification, reference being had to the accompanying drawing, forming part thereof.

The figure is a plan view of a stickpin, showing my new design.

I claim:

The ornamental design for a stickpin, as shown.

NEHEMIAH P. CORNEY.
